INSERTING MACHINE

Johan Marinus Hatersel Koning, Hillegersberg,
Netherlands, assignor to Leonard Evers and
Jaap Kars, both of Rotterdam, Netherlands

Application February 3, 1932, Serial No. 590,690
In Germany February 14, 1931

15 Claims. (Cl. 271—39)

The invention relates to the art of assembling of papers and has particularly reference to a machine for automatically delivering single copies from a stock of papers.

5 An object of my invention is to provide a machine for feeding single copies from a stock to a machine for further treatment.

Another object of the invention is to provide a machine for automatically detaching single 10 copies from a stock of vertical papers and piling them horizontally.

A further object of the invention is to provide a machine for entirely automatically delivering in an efficient manner and with high speed single 15 copies to an inserting machine, in regular intervals of time.

The invention also consists in a machine for automatically transforming a vertical pile of papers of any given quantity into a horizontal 20 pile of a limited quantity and feeding the papers from the last successively in timed relation and equal intervals into conveyors leading to a machine for further treatment.

The form of the machine, which I have chosen 25 to illustrate my invention, includes a plurality of conveyors, a rotating roller cooperating with the belts, an inclined board and rotating fingers, so that a copy supplied by the rotating roller and stopped by the inclined board may be withdrawn by the fingers.

The various novel features of my invention 30 will be apparent from the following description and drawings and will be particularly pointed out in the claims.

35 In the drawings Fig. 1 is a side-elevation disclosing a form of execution of the invention,

Fig. 2 a side-view on the same scale, showing certain details of construction with parts broken away.

40 Fig. 3 is an enlarged side-view of a portion of the machine, showing the inclined board in section.

Fig. 4 is a front-view of that board on the same scale.

45 Fig. 5 is a front-view of another portion of the machine, showing the propeller roller with gearing.

Fig. 6 is an end-view with some parts broken away of the preferred means for controlling the 50 supply.

Figs. 7 and 8 show the electric circuits, respectively for controlling the supply and for controlling the height of the horizontal pile.

55 The machine illustrated includes upright frame

members 1 and 2 and conveyors 3, 4 and 5, suitably supported between the frame members.

Referring to Fig. 2 of the drawings, the composition of the machine will be cleared.

Between the frame members a roller 6 is 60 mounted, situated between the conveyors 3 and 4. The conveyor 4 leads from the roller 6 to an inclined board 7, movably connected to the frame members by a support 8. Between the edge 9 of the board and the conveyor 4 a narrow passage 65 is left, partially blocked by a resilient tongue-piece 10, adjustably connected to the main board. Mounted adjacently to the front-side of this board are rotating fingers 11 on shafts 12 carried by disks on a shaft 14 between the frame members. The conveyor 5 is guided by suitable rollers and by the disks and is mounted partially adjacent and parallel to the conveyor 4, the upper part of this last conveyor being horizontal and constituting a base for the horizontal papers 75 which rest before the slot between the inclined board 7 and the conveyor 4.

Adjacent to the roller is a shaft 15, carrying striking arms 16, suitable means being provided to rotate the arms synchronously with the 80 roller 6.

Suitable mechanism is provided for controlling automatically the supply of papers to the horizontal pile by stopping the feeding roller 6 when the number of copies on the horizontal belt surpasses a prefixed amount. Also suitable mechanism is provided for controlling automatically the progress of the belt 3, means being provided for stopping automatically the motion of this belt 85 as soon as the vertical pile has acquired the desired inclination relative to the roller.

According to my invention, a bunch of papers A with their folded edge at the top and forward are deposited on the front-portion of the conveyor 3, resting against the roller 6 under an inclination, dependent from the quality of the papers. The friction with the revolving roller withdraws the foremost copy and lifts it, until it is bent towards the roller by the striking arms 16. The copy is withdrawn and forwarded to the horizontal pile in front by the roller 6, by friction with its surface. The bottommost copy of this 90 last pile B is transported by friction with the conveyor 4 through the slot between the board 7 and the conveyor 4, against the resilient tongue-piece 10, so as to protrude enough from the pile 100 to be gripped by the rotating fingers passing along the tongue-piece and withdrawing the bottom-copy.

105 Referring to Fig. 3 it will be seen that the 110

other copies are held back by the inclined board till the bottommost one is withdrawn through the narrow slot. The pile which rests before the slot has a stepped form, caused by the sloping board 7, so as to facilitate the withdrawing of the one copy after the other. It has to contain only a few copies, so as to prevent the slot from getting blocked when the upper copies might press so heavily on the bottommost one that at 10 the withdrawal more than one gets into the slot.

One feature of my invention is the transforming of the main pile A deposited haphazardly on the first belt 3. It is transformed into a light pile with stratified copies. The number of copies 15 to rest on the second belt 4 may be controlled by the speed of the roller 6.

Referring to Fig. 2 of the drawings, the support is provided with a swiveling finger 17, the end of which rests on a predetermined distance 20 above the horizontal part of the belt 4. This finger turns a shaft 18 and opens an electric circuit leading to a magnetic clutch in the gearing, driving the roller 6. The details of this construction will be explained afterwards.

Another feature of my invention is the automatic withdrawal of only one copy from the vertical pile by friction with the roller.

I prefer to control automatically the inclination of the foremost copies of that pile, so that 30 they may stand under a useful angle on the conveyor 3 and are struck by the roller 6 on the right place.

Referring to Fig. 2 the automatic device consists in a finger 19, activating an electromagnetic clutch in the driving gear of the conveyor 3. As 35 soon as the foremost copy has reached with its under edge the desired position on the conveyor, a switch is broken and the progressive motion of the belt 3 is stopped.

When the vertical pile might tumble down or slide away the electric circuit is restored by the finger 19 activating the switch and the conveyor gets into motion, till the pile has reached the desired position.

The finger 19 oscillates on a shaft 20, supported in brackets 21. The shaft 20 is provided with links 22, carrying a circuit-breaker 81. Fig. 6 shows these pieces, connected with a conduct 40 leading to brushes 23 resting upon conducting rings 24 fixed to a box 25, connected to the shaft 26 and containing an electromagnetic clutch 27 the box 25 being carried to the shaft and constituting the fixed part of the clutch. This shaft is supported between the 45 frame members 1 and 2 and carries a gearing wheel 28, provided with a friction disk 32 and fitted loosely on the shaft. At the end of the shaft a worm 29 is fixed, driving by means of the wormwheel 30 and pinionwheel 31 the propelling mechanism of the conveyor. When the 50 circuit is closed by the contacts 23, 24, the electromagnetic clutch is actuated and the gearing wheel 28 drives by adhesion the box of the clutch, which is keyed on the shaft. In this way the shaft 26 and the conveyor are driven by the main 55 mechanism. As soon as the stack of papers on the conveyor reaches the correct position, its under end touches the fingers 19 and lifts the contact-pieces 23 from the rings 24. The circuit is broken then and the machinery of the 60 conveyor is stopped.

Referring to Figures 2 and 5, the mechanism controlling the height of the horizontal pile of copies consists in a finger 17 connected to a 65 shaft 18, oscillating in the frame. The shaft

actuates a switch in the circuit leading to an electromagnetic clutch, connected to the frame. The movable part 33' of this clutch is fixed as by nut 34' to the shaft 34 of the driving mechanism of the roller 6. On this shaft is keyed the 80 gearing wheel 35, driven by the main machinery, while to the same shaft is fixed a friction disk 36, capable of operating upon the friction disk 37 fixed to the shaft 38, carrying a pinion wheel 39 driving the pinion wheel 40 on the shaft 41 of the roller 6. Fixed to this shaft is also a transmission wheel 41 driving the wheel 42, rigidly connected to the shaft 43 of the striking arms 16.

When the supply of single copies surmounts a certain number, the finger 17 (Fig. 2) is lifted, the circuit broken, the clutch 33 is no longer activated and the friction disk 36 is free from the friction wheel 37, so that the shaft 38 and herewith the roller 6 is stopped. After decrease of 90 the number of sheets to a desired level, the finger 17 swings downward and closes the switch and herewith the circuit to the clutch.

Referring to Fig. 3, the special part for stratifying the horizontal pile in a stepped formation 95 consists in the inclined board 7, connected to a support 8, mounted between the frame parts. The under edge of this board protrudes lightly inwards and lies above the horizontal conveyor 4 at a distance, large enough to allow the passage 100 of one copy. Adjustably connected to this board is a feathering tongue-piece 10, which closes partially the slot between the under edge 9 of the board and the conveyor 4. This tongue-piece is connected to the support by a pin 50, cooperating with a screw 51. A spring 52 detains the 105 slideable tongue-piece in its lowermost position until it is raised by turning the screw. The board is provided with ports 53, through which pass the gripping elements of the withdrawing device. 110 The whole support with its attached board can be lifted by means of the screw 54 and the spring 55.

Referring to Fig. 3, the bottommost copy is 115 withdrawn by fingers 56 connected to holders 11, 120 oscillating on shafts 12 supported in rotating disks 57. The shafts are provided with cranks 58, fitted with rollers 59 running at the revolutions of the disks 57 over an unround disk 60 fixed adjustably to the machine. In this way by judicious choice of the form and location of the disk 60, the fingers 56 may be forced to strike the bottommost copy in the right position and withdraw it at the further revolution through the narrow passage under the feathering tongue-piece.

Referring to Fig. 2 it may be seen, that in this 125 way the copy is caught between the conveyor 4 and the other conveyor 5, further led around the roller 61 along the roller 62, and between the rollers 63 and 64, from where it is taken for further treatment. The conveyor 4 is led along the horizontal part by the rollers 67 and 61, along the roller 62 and the rollers 64, 65 and 66.

The upper conveyor 5 is led around disks on 130 the shaft 14, along the roller 61 and further by 135 the rollers 62, 63, 68 and 69.

The conveyor 3, carrying the stack of papers, is 140 led by rollers 70 and 71 and may run over rollers 72, 73 and 74. This conveyor is preferably made of elastic material and propelled by the gearing 145 shown in Fig. 1 and partially described herebefore. The stacked papers standing on the belt 3 may be guided laterally by bars 75 and 76.

The electric circuit governing the speed of the conveyor 3 consists of the mentioned conduct 150

leading over the switch 81 to the brushes 23 and over rings 24 to a coil 82. The current is fed from a battery 83 or other source.

The system controlling the quantity of copies retarded before the inclined board consists in the finger 17 on the shaft 18, operating the circuit breaker 86 in the conduct 85, leading to the coil 87 and the battery or other source 88.

What I claim is:—

- 10 1. In a mechanism of the class described, in combination, means for stacking a pile of sheets standing upright including a horizontal endless conveyor, means for guiding and delivering the said sheets singly and progressively to a pile of 15 horizontal sheets, means for offsetting this pile, means for forwarding the bottommost sheet of said horizontal pile, and means for withdrawing at predetermined intervals this bottommost sheet and pulling it into a set of conveyors. 80
- 20 2. In a mechanism of the class described, in combination, means for stacking a pile of sheets standing upright, means for maintaining a constant inclination of the upright pile of sheets, means for detaching the foremost of the sheets, 85 means for forwarding it unto a horizontal pile, means for retaining the sheets of the horizontal pile, means for forwarding the bottommost sheet of the horizontal pile, and means for pulling the bottommost sheet from the horizontal pile. 90
- 25 3. In a mechanism of the class described, in combination, means for stacking a pile of sheets standing upright including a horizontal endless conveyor, guides above the conveyor, a rotating drum situated at one end of the conveyor detaching the foremost of the sheets, means for forwarding it unto a horizontal pile, means for offsetting said pile in a stepped formation, means for forwarding the bottommost sheet of the horizontal pile and means for withdrawing the bottommost sheet of the horizontal pile into a set of conveyors. 100
- 30 4. In a mechanism of the class described, in combination, means for sustaining a standing pile of sheets so that each of the sheets assume a vertical position, means for controlling the inclination of this pile, means for detaching the foremost sheet of this pile, means for forwarding it towards a horizontal pile, means for detaching the bottommost sheet from this horizontal pile. 105
- 35 5. In a mechanism of the class described, in combination, means for detaching the foremost of a standing pile of sheets, means for controlling the speed of the detaching apparatus, means for forwarding the withdrawn copy and means for delivering it into a conveying apparatus. 110
- 40 6. In a mechanism of the class described, in combination, means for stacking a pile of sheets with the folded edge at the top, means for lifting the foremost, means for bending it horizontally, means for forwarding it to a horizontal pile, means for stratifying this pile, means for detaching the bottommost sheet and withdrawing it, means for retaining the upper copies of the same pile. 115
- 45 7. In a machine of the class described, a conveying belt, a rotating drum, revolving striking arms, a second conveying belt, an inclined board above this belt with its under edge at a small distance from this belt so as to provide a slot, a resilient partial closure of the slot between the 120
- 50 board and the belt, and means frictionally engaging and for withdrawing a single copy at a time through this slot. 125
- 55 8. In a mechanism of the class described, in combination, a conveying belt, an oscillating finger connected with a circuit breaker at the end of this belt, an electromagnetic clutch in the propelling mechanism of this conveyor, a revolving drum above and situated at the end of the belt, rotating striking arms above this drum, a second conveying belt, an inclined board above this belt and means for withdrawing the copies through the slot between the board and the belt, with means for controlling automatically the quantity of copies resting upon this belt. 130
- 60 9. In a mechanism of the class described, in combination, a conveyor, a drum, striking arms above this drum, means for stopping automatically the movement of this belt, a second conveying belt, an oscillating finger at a certain distance above this belt, hinged on a shaft in the frame and operatively connected with a circuit breaker in a circuit leading to an electromagnetic clutch in the driving mechanism of the drum. 135
- 65 10. In a mechanism of the class described, in combination, an inclined board connected to the frame of the machine, a receding under-edge of this board, a resilient tongue-piece adjustably connected to this board, and means for lifting the board so as to adjust the size of the slot between the board and the conveying belt. 140
- 70 11. In a mechanism of the class described, in combination, means for forwarding automatically single copies from a stack of folded papers, with a revolving drum containing gripping fingers, said fingers acting upon the forwarded folded copies in timed intervals. 145
- 75 12. In a mechanism of the class described, in combination, means for forwarding automatically in timed intervals single folded copies of a paper from a vertical stack of sheets, gripping fingers for withdrawing the forwarded copy, a drum for rotating said fingers, with means for moving the points of the fingers along a prescribed curvilinear path. 150
- 80 13. An improvement in the art of inserting, which consists in reducing a vertical stack of papers to a horizontal pile of less and limited number, moving this pile and during the movement stopping the upper papers for producing a stepped offset formation, forwarding the bottommost paper, and then retarding said paper and withdrawing it in timed intervals. 155
- 85 14. In a mechanism of the character described the combination, means for sustaining a standing pile of sheets so that each of the sheets assumes a vertical position, means for detaching the foremost sheet of the vertical part, means for forwarding the detached sheet to a horizontal pile, mechanism for controlling automatically the supply of papers to the horizontal pile when the number of copies on the horizontal pile passes a fixed amount, and means for detaching the bottommost sheet from the horizontal pile. 160
- 90 15. A mechanism as claimed in claim 14, wherein means is provided for maintaining a constant inclination of the upright pile of sheets. 165

JOHAN MARINUS HATERSEL KONING.
